UNITED STATES PATENT OFFICE

NICHOLAS V. DI LORENZO, OF BUFFALO, NEW YORK

ELECTRIC HEATER AND STOVE

Application filed September 5, 1931. Serial No. 561,447.

This invention relates to a combined heater and stove, the object of the invention being to provide a heater and stove of simple construction so that it may be manufactured at nominal cost and which will be efficient and practical in operation.

A still further object is to provide in a construction of the character above suggested, a novel arrangement of dampers, shelves, and heating means whereby the use of the device as a cooking stove or as a heater can be readily and easily effected.

Still another object of the invention is to provide an article of this character which will possess sufficient ornateness so as to present a pleasing appearance, without in any wise detracting from its utility.

Still a further object of the invention is to provide a combined electric heater and stove, to the interior of which access may be easily had for removing or replacing the trays and heating elements.

Other objects and advantages of the invention will become apparent from a study of the following description, taken in connection with the accompanying drawings wherein:

Figure 1 is a rear elevational view of the electric heater and stove.

Figure 2 is a front elevational view thereof.

Figure 3 is a side elevational view thereof.

Figure 4 is a top plan view thereof, certain parts being broken away and shown in section.

Figure 5 is a vertical transverse sectional view therethrough.

Figures 6 and 7 are horizontal transverse sectional elevational views taken through the structure.

Figure 8 is a plan view of an end portion of a slidable draft door.

Figure 9 is a perspective view of a corner portion of the tray.

Figure 10 is a plan view of a foldable damper.

Figure 11 is a fragmentary perspective view of the foldable damper, and guide therefor, the damper being partially folded in position.

Figure 12 is a front elevational view, on a

reduced scale, of a modified form of the invention.

Having reference more in detail, 5 designates generally a pan shaped bottom member supported on legs 6 and rising from the bottom member 5 is a substantially rectangular casing 7 having rounded corners as shown in Figure 7 and including a front wall 8, rear wall 9, and side walls 10. A cover 11 is provided for the casing and may be readily removed therefrom.

A water tank 12 is supported in the upper portion of the casing and is equipped with a filling neck 13 extending through the top 11 and provided with a closure cap 14. A suitable drain 15 is provided for the tank 12 as well as a water gauge G.

Two parallel rows of relatively spaced draft ports 16 are provided in the bottom 5, and each row of ports is controlled by a slotted draft door 17 constrained to slide in guides 18.

Located within the casing 7, and supported on the bottom member 5, is a substantially frusto-conical cam shaped deflector 19, opposite side portions of which extend over the draft opening 16 and serve to deflect the current of air passing upwardly through the casing.

Disposed slightly above the deflector 19, and located in each corner of the casing 7 is a suitable disk like supporting lug 20, and below each lug 20, is a lug 22 to which is bolted or otherwise secured thereto as at 24 a tongue provided at the corner of the deflector 19.

The upper lugs 20 support a frame 23 of insulated material, and between opposed members of the frame 23 are coiled conducting wires 25 of suitable resistance. A switch S for the heater is mounted on the front wall 8 of the casing.

It has been found, that the best means of heating air in a room will be obtained by providing an opening 26 in the upper portion of the rear wall 9 and elongating the opening horizontally. Stretched across the opening, and supported in any suitable manner, is a screen 27 and controlling the opening is a hinged draft door 27. A latch de-

vice 28 is employed for retaining the draft door in a closed position. The hinge rod 29 of the door 27 projects beyond one side wall of the casing and is equipped with a handle 29a to facilitate swinging of the door 27 to an opened or closed position. Suitably mounted on the bottom wall of the tank 12 is a stop 30 for limiting inward swinging movement of the door 27 to an open position. (See Figure 5.)

A well known type of slide damper 31 consisting of screening and slotted sliding plate, is provided on the rear wall 9 adjacent the lower portion of the casing.

15 In the front wall 8 is provided a relatively large sight opening 32, and the opening may be closed either by a suitable transparent panel 33 mounted in a groove 34 extending about the opening 32, as shown in Figure 5, or by a single door, or a double hinged door such as suggested at 35 in Figure 12.

20 Access to the interior of the casing 7 is gained through openings provided in the side walls 10, and doors 36 are provided for the openings.

25 Supported on the front and rear walls of the casing, adjacent the corners thereof, are interior vertical angle bars 37, each of which has one edge thereof serrated or otherwise to provide a series of vertically spaced lugs 38 whereby to support in horizontal positions within the casing, shelves 39 and a tray 40.

30 The shelves 39 are perforated, and may be of any suitable construction, as for example and as shown, each shelf is formed of wire and includes a frame having longitudinal and transverse wires mounted therein. The tray 40 is pan shaped and the peripheral wall of the tray at each corner thereof is provided with a pair of lugs 41, 42, the lugs 41 projecting from the end walls of the tray for spacing the ends of the tray from the side walls 10 of the casing and the lugs 42 engaging selective lugs 28 for supporting the tray in proper position.

35 The tray, shelf and heating element including frame 23 may be readily placed within or removed from the casing through the openings in the side walls 10 of the casing.

40 When the device is used for cooking purposes, articles of food may be placed on the shelves 39 or the pan 40 and the air rising upwardly through the casing and heated by the heating element, will warm and heat the food.

45 Mounted in the casing 7 considerably above the bottom 5 are opposed transverse guide rails 44 between which are disposed the sections of a folding damper designated generally by the reference character 45. Each section of the damper includes a pair of leaves 46, 47 hinged together as at 48. Each leaf 47 is provided with pintles 49 extending

50 through the walls 10 of the casing 7 and provided with suitable knobs. Each leaf 46 is provided with guide pins 50 ridable on the upper edges of the guides 44. Obviously by rotating the pintles 49, the sections of the damper may be extended or closed as shown in full lines in Figure 5, or folded to a fully opened position as shown in dotted lines in said figure, or partially open or folded as suggested in Figure 11.

55 When the device is being used as a stove, that is for cooking or warming articles of food, the damper door 27 and sliding draft 31 are closed and the foldable damper may be in a fully closed or partially closed position as found desirable.

60 On the other hand when the device is to be used for heating purposes, that is for heating a room or the like, door 27 is open, the foldable damper is fully open, and the sliding draft 31 suitably regulated.

65 The water tank 12 will serve as a humidifier, and if desired, may be also used for brewing tea, by merely inserting the tea bag into the tank through the opening 13.

70 The entire construction is relatively light in weight and when used as a stove, the device may be so arranged as to have the front wall 8 thereof faced into the room. The side walls 10 of the combined heater and stove are equipped with handles 43 to facilitate moving the device from one place to another and for turning the device for facing either the front or rear walls to the room, the rear wall 9 facing the room when the device is used as a heater.

75 It is of course to be understood, that the walls of the combined heater and stove may be suitably constructed for heat resistance purposes, being either in the nature of double walls or walls lined with asbestos or like material. Also it is to be understood that in lieu of the resistance coils 25, resistance rods may be used.

80 Even though I have herein shown and described the preferred embodiments of the invention, it is to be understood that the same is susceptible of further changes, modifications and improvements coming within the scope of the appended claims.

85 Having thus described my invention, what I claim as new is:

1. A combined heater and stove comprising a casing, legs supporting the casing, the bottom of the casing having openings therein, a slide for controlling the openings, an inverted conical deflector in the lower end of the casing for deflecting the air passing through the openings towards the sides of the casing, a heating element located in the casing above the deflector, removable shelves located in the casing and above the heating element, a damper member located in the casing an appreciable distance above the heating element, means for moving said damper member to open and closed position from the

exterior of the casing, one wall of the casing having an opening therein adjacent its upper end, a door closing the opening, and said wall having an opening therein located slightly above the heating element and manually operated means controlling the last-mentioned opening.

2. In a combined heater and stove, a casing, legs for supporting the casing, a pair of rows of openings in the bottom of the casing, one row being located adjacent one side of the casing and the other row adjacent the opposite side, a slide for controlling each row of casings, a deflector in the bottom of the casing for directing the air passing through said opening towards the sides of the casing, a frame located in the casing slightly above the deflector and contacting the sides and ends of the casing, and forming an opening above the deflector, heating elements carried by the frame and extending across the openings formed thereby, one wall of the casing having an opening in its upper part, a door for controlling the opening, said wall having an opening therein arranged slightly above the heating element, manually controlled means for controlling said opening last mentioned, a damper member located in the casing slightly above the plane of the last-mentioned opening, and manually operated means extending thru a part of the casing for moving said damper member to open and closed position.

3. In a combined heater and stove, a casing, heating means in the lower part thereof, and a damper for separating the lower part of the casing from the upper part thereof, said damper comprising two pairs of plates, the plates of each pair being hingedly connected together, rails in the casing, pins carried by the ends of the inner plates of each pair for engaging the rails, projections on the ends of the outer plates of each pair, said projections extending through the casing and having knobs on their outer ends, whereby by turning the knobs, the plates will be moved to open and closed position.

In testimony whereof I affix my signature.
NICHOLAS V. DI LORENZO.
